UNITED STATES PATENT OFFICE.

WILLIAM H. WHITE, OF QUINCY, MASSACHUSETTS, ASSIGNOR TO REGAL SHOE COMPANY, OF WHITMAN, MASSACHUSETTS, A CORPORATION OF MASSACHUSETTS.

STAND FOR FITTING SHOES.

Application filed September 22, 1924. Serial No. 739,056.

This invention relates to a stand for conveniently supporting the foot of a customer, either for the purpose of trying on and fitting shoes or for polishing shoes, or other purposes where it is desired to present the foot to the operator or salesman in a convenient position.

In its general features the invention comprises a supporting base in which is mounted a slideable plunger carrying at its top a foot rest, said plunger being shiftable automatically to operative position for use, while being capable of being depressed to lowered position in which the foot rest lies close to the supporting base so as not to form an obstacle to the customer when taking or leaving his seat.

Another feature of the invention consists not merely in the automatic raising of the foot rest to operative position for use, but also in the provision of elastic means for yieldingly supporting the foot rest in such position. Another feature of the invention resides in the combination with such a slideable foot support with pneumatic apparatus by which its movements are effected and controlled.

These and other features of the invention will be set forth in the following specification and will be defined in the claims hereto annexed.

In the accompanying drawings I have illustrated a simple form of construction and arrangement embodying the principles of this invention, in which:

Figure 1 is a sectional elevation showing a stand or platform equipped with my improved foot support.

Figure 2 is a detail view showing, in cross section, the valve chamber and valve by which the compressed air that is utilized to operate the device is applied and controlled.

Figure 3 is a detail view showing, in central vertical section, the construction of the sleeve or plunger secured to the floor of the platform to support the slideable foot support member.

In the practice of this invention according to the form illustrated in the drawings, I have mounted the foot rest in a raised platform 1, which may be provided with a chair or other suitable seat for the customer, partly indicated at 1^a. The fixture or bracket which forms the supporting element for the foot rest member is shown in the

form of a sleeve 2, provided with a peripheral flange 3, arranged in an oblique plane to the axis of the sleeve in order to allow the foot rest to move upward at an oblique angle to the floor. The attaching flange 3 is secured to the underside of the floor of the platform by means of suitable attaching screws.

Mounted in this sleeve is a slideable plunger 4, carrying at its upper end a plate or foot rest 5, which is preferably pivoted to the upper end of the plunger by pivot pin 6, passing through the plunger, and a depending lug 5^a. The upper end of the plunger is cut off so as to present two angular faces 4^a and 4^b, the former extending in a substantially horizontal plane, the latter in a downwardly inclined plane so as to form stops or supports for the pivotal foot rest in its lowered position and in its raised position, respectively, the latter being so disposed as to give the foot plate a convenient angle for sustaining the foot of the customer when seated in the chair.

The sleeve 2 is provided at its lower end with an enlarged socket in which is tightly secured or seated the upper end of a piston tube or chamber 7, and the annular shoulder against which the end of the tube abuts is provided with a notch 22 to engage and guide a guide pin 4^c projecting from one side of the plunger 4 when the plunger is in raised position. This notched shoulder forms also a stop to limit the upward movement of the plunger under the pressure of the elastic medium employed to raise it to service position. On the lower end of the plunger is secured an air-tight piston 10 which, in the form shown, is acted upon by compressed air admitted at will above and below the piston in order to give it the desired downward or upward movement.

The piston chamber is provided above the uppermost position of the piston with a port 11, connected by an air tube 12, with the valve chamber 15.

The lower end of the piston chamber is also provided with a port 13 which is connected with the air chamber 15 through the air pipe or tube 14. A compressed air supply pipe 16 is also connected with said valve chamber from a suitable source of supply, and in the valve chamber is mounted a rotatable two-way valve plug 17 which is operated through the medium of an up-

wardly projecting valve stem 18 and a handle 18^a secured thereto. An exhaust port 19, arranged opposite the intake passage 16, serves to allow air to escape from one side of the piston while it is being admitted into the other side.

The flow of the air will be understood by reference to Figure 2, in which the different nipples 12^a, 14^a and 16^a are numbered in accordance with the different pipes communicating therewith. According to the illustration of Figure 2, the position of the two-way valve is such as to place the supply pipe in communication with the port 13, through tube 14, to raise the piston and foot rest while the passage on the other side of the valve establishes communication between the port 11 and the exhaust port 19 of the valve chamber. When it is desired to lower the foot rest, the shifting of the valve through an arc of 90 degrees in a counter-clockwise direction opens communication between the exhaust 19 and port 13 at the lower end and introduces compressed air above the piston. In this position the plunger descends until the foot rest 5 comes into contact with the floor of the platform upon which it lies snugly, as indicated in dotted lines in Figure 1.

The ports in the piston chamber are of such relatively small area compared with the surface of the piston as to prevent any severe shock resulting from the induced movement of the plunger from one position to the other. The use of a compressible medium for raising and supporting the plunger provides a certain elasticity for the foot rest. The valve, when turned to directly close either opposite pair of ports in the valve chamber, can be used to confine any desired volume of air in the lower end of the piston chamber so that if, after the customer has placed his foot on the rest, it is found too high for his individual convenience a part of the supporting volume of air may be vented and the valve chamber closed so as to allow the foot rest to stand at a somewhat lower level where it is supported by the elastic confined body of air against the downward pressure of the foot.

The upper end of the sleeve 2 is provided with a recess forming a stuffing box into which is fitted a gland 21 to prevent leakage of air from the piston chamber.

What I claim is:

1. A stand for shoe fitting embracing in combination a supporting sleeve, a piston

chamber, a piston plunger slidable up and down through said sleeve and chamber by compressed air admitted to said chamber 60 and provided at its upper end with a foot-rest, and guiding means for preventing the rotation of said plunger about its axis when the plunger reaches the top of its traverse, substantially as described.

2. In a shoe fitting stand having a raised platform and a seat, the combination of a foot-supporting rest embracing an oblique bearing sleeve secured in the platform floor in front of the seat, a downward tubular 70 extension secured thereto and forming a piston chamber, a piston plunger slidably mounted in said sleeve and chamber to respond to unbalanced pressure of air upon opposite sides of the piston, a foot-plate 75 connected to the upper end of said plunger by a loose connection permitting it to lie flat upon the platform floor when the plunger is lowered, and means for controlling the inflow and the exhaust of air on 80 opposite sides of the piston to raise and to lower the plunger and foot-rest at will.

3. In a shoe fitting stand having a raised platform floor, the combination of a bearing sleeve secured thereto to project downward below the platform, a downward extension of said sleeve adapted to form a piston chamber for a piston plunger mounted in said sleeve, means for admitting into said chamber and exhausting therefrom at will 90 compressed air to raise or lower said plunger, a foot-rest plate mounted on the upper end of said plunger and formed to lie flat against the top of the platform when lowered, and an air-tight packing gland located in the 95 upper recessed end of said sleeve to prevent leakage as the piston slides to and fro.

4. In a shoe-fitting stand having a raised platform, the combination of a downwardly and rearwardly inclined bearing sleeve having an attaching flange securing it to the underside of the platform floor and having a packing gland located in its upper end, a piston chamber forming a downward continuation of said sleeve, a piston plunger mounted in said sleeve, a foot-rest plate mounted on the upper end of said plunger, said piston chamber being provided with ports on opposite sides of the piston for admitting or exhausting compressed air at the will of the operator.

In witness whereof, I have subscribed the above specification.

WILLIAM H. WHITE.
